ELECTRIC INCANDESCENT LAMP

Kazuo Setoguchi, Tokyo, Japan, assignor to General Electric Company, a corporation of New York

Application May 26, 1933, Serial No. 673,661
In Japan May 31, 1932

5 Claims. (Cl. 176—4)

My invention relates to electric incandescent lamps and similar devices and more particularly to energy translation elements therefor having the form of ribbons or strips.

5 The object of my invention is to provide a novel method for producing ribbon shaped energy translation elements which comprises winding a coil of filamentary wire and subsequently flattening or pressing the same into the shape 10 of a ribbon, preferably by passing the coil between a pair of rollers. In a modified method, the coil is wound around a mandrel and compressed, together with the said mandrel. As 15 compared with the present method which consists of rolling out a single wire of circular cross-section, my method is much more easily performed and the finished ribbon has a rough surface, providing a greater active surface area. Moreover, when used as a filament for an electric 20 incandescent lamp, the ribbon made according to my method is substantially free from deformation or sagging. Further features and advantages of my invention will appear from the following detailed description.

25 In the drawing, Fig. 1 is a diagrammatic representation of a method of producing a ribbon shaped energy translation element according to my invention; Fig. 2 is a diagrammatic representation of a modified method; and Fig. 3 is an elevation of an electric incandescent lamp containing a filament comprising my invention.

Referring to Fig. 1, a filamentary wire of refractory metal such as tungsten or molybdenum is wound into a coil 10 and preferably cut 30 into lengths which are then passed between a pair of rollers 11—12, causing said coil to be flattened or pressed into a ribbon or strip 13. The surface of said ribbon 13 is rough, due to the remaining visible traces of parallel lines 35 formed by the individual turns of the coil. The ribbon 13 is substantially free from distortion even when operated at incandescence in an electric lamp due to the effects of the rolling operation which removes the coiling strains in coil 10. The said coil 10 is preferably fed into the rollers 11—12 in the direction of the axis thereof so that the turns overlap as they are pressed by said rollers, as shown in the drawing. In this manner a flat ribbon 13 of any desired thickness

may be obtained easily by a single passage between the rollers.

In Fig. 3 is shown an electric incandescent lamp containing the ribbon type energy translation element or filament 13. Said filament 13 is mounted on leading-in wires 14 and sealed in a bulb 15 having a base 16 mounted thereon.

In a modified method, illustrated in Fig. 2, a coil of wire 17 is wound around a mandrel 18. The said coil 17, together with the mandrel 18, 10 is then passed between the rollers 11—12 which flatten or compress the structure into the shape of a ribbon or strip 19. The individual turns of the coil in this case do not incline and overlap as in Fig. 1. The rolling operation removes the 15 coiling strains existing in the coil 10 and produces a ribbon 19 which is twisted throughout its length and is substantially free from deformation even when operated at incandescence in a lamp.

What I claim as new and desire to secure by Letters Patent of the United States is:

1. The method of producing an energy translation element for electric lamps and similar devices which comprises winding a wire around a 25 mandrel to form a coil thereon and subsequently pressing said coil and mandrel into the shape of a ribbon.

2. The method of producing an energy translation element for electric lamps and similar 30 devices which comprises winding a wire around a mandrel to form a coil thereon and passing said coil and mandrel structure between a pair of rollers to press said structure into the shape of a ribbon.

3. A filament for electric lamps and similar devices consisting of a ribbon formed by compressing a coil of refractory metal and having a rough surface caused by traces of the individual turns of the coil.

4. A filament for electric lamps and similar devices consisting of a ribbon formed by compressing a coil of tungsten and having a rough surface caused by traces of the individual turns of the coil.

5. A filament for an incandescent electric lamp consisting of a ribbon of tungsten having a coiled tungsten filament surrounding and compressed against the flat surfaces thereof.

KAZUO SETOGUCHI.
